CLAIM

The ornamental design for an auto rack railroad car restraint end cap, as shown and described herein.

DESCRIPTION

FIG. 1 is a perspective view of an auto rack railroad car restraint end cap of our new design.

FIG. 2 is a rear view of the auto rack railroad car restraint end cap of our new design illustrated in FIG. 1.

FIG. 3 is a front view of the auto rack railroad car restraint end cap of our design illustrated in FIG. 1.

FIG. 4 is a right side view of the auto rack railroad car restraint end cap of our new design illustrated in FIG. 1, the left side view being a mirror image thereof; and,

FIG. 5 is a top view of the auto rack railroad car restraint end cap of our new design illustrated in FIG. 1, the bottom view being a mirror image thereof.

1 Claim, 4 Drawing Sheets

Related U.S. Application Data

is a division of application No. 14/319,147, filed on Jun. 30, 2014, now Pat. No. 8,961,084.
